(57) **CLAIM**

The ornamental design for an aircraft belly fairing, as shown and described.

DESCRIPTION

FIG. 1 is a perspective view taken from a top, left side of an aircraft belly fairing according to our new design;

FIG. 2 is a left side elevation view thereof;

FIG. 3 is a right side elevation view thereof;

FIG. 4 is a bottom plan view thereof;

FIG. 5 is a front elevation view thereof;

FIG. 6 is a rear elevation view thereof;

FIG. 7 is a perspective view taken from a top, front, left side of the aircraft belly fairing of FIG. 1 shown on an aircraft shown in broken lines;

FIG. 8 is a left side elevation view of FIG. 7;

FIG. 9 is a right side elevation view of FIG. 7;

FIG. 10 is a bottom plan view of FIG. 7;

FIG. 11 is a front elevation view of FIG. 7; and,

FIG. 12 is a rear elevation of FIG. 7.

Throughout the Figures, broken lines showing environment or structure are for illustrative purposes only and form no part of the claimed design.
